CLAIM

USPC **D32/2**

The ornamental design for a dishwasher door and control panel, as shown and described.

(58) **Field of Classification Search**

DESCRIPTION

USPC D32/1, 2; D15/91; D7/405-406
 CPC .. A47L 15/00; A47L 15/0002; A47L 15/0005;

FIG. 1 is a top perspective view of a dishwasher door and control panel showing our new design according to a first embodiment;

A47L 15/0007; A47L 15/0076

FIG. 2 is a front view of the top cap combined with front control of FIG. 1;

See application file for complete search history.

FIG. 3 is a top view of the top cap combined with the front control of FIG. 1;

FIG. 4 is a right side view of top cap combined with the front control of FIG. 1, the left view being a mirror image; and,

FIG. 5 is an enlarged front view of top cap combined with the front control of FIG. 2.

(56) **References Cited**

The broken lines in the figures illustrate the portions of the design that form no part of the claimed design.
